UNITED STATES PATENT OFFICE.

DUGALD DRUMMOND, OF SURBITON, ENGLAND.

LOCOMOTIVE-BOILER.

SPECIFICATION forming part of Letters Patent No. 629,893, dated August 1, 1899.

Application filed February 16, 1898. Serial No. 670,467. (No model.)

To all whom it may concern:

Be it known that I, DUGALD DRUMMOND, engineer, of South Bank Lodge, Surbiton, in the county of Surrey, England, have invented 5 new and useful Improvements in Locomotive-Boilers, of which the following is a specification.

This invention, which relates to boilers for locomotives, has for its object to enhance the 10 steam-raising capacity of such boilers; and to that end it consists in the provision of an arrangement of water-tubes so connecting the sides or walls of the fire-box that a rapid circulation of water around these walls is produced, while a large heating-surface is added 15 to the boiler.

The invention is illustrated by the accompanying drawings, in which—

Figure 1 is a longitudinal elevation of the 20 fire-box end of a locomotive-boiler, and Fig. 2 is a cross-section of the same.

As represented in the drawings, the fire-box is of the ordinary shape, but in the sides or 25 walls of the inner shell A orifices are formed for the reception of water-tubes B, extending across the fire-box and the ends of which are expanded or otherwise secured in the side walls. These tubes are inclined and are fitted in two sets—one set in proximity to the firing- 30 door G being inclined in one direction and the set behind inclined in the opposite direction—to promote circulation of the water in the spaces C between the inner and outer shells A and D of the fire-box. These water- 35 tubes are fully exposed to the heat of the furnace, which latter may be of the usual type in locomotives and the gases from which may partly circulate among the tubes A on their way to the fire-tubes H, leading to the smoke-

box, which are secured in the tube-plate I at 40 the rear of the fire-box in the ordinary way.

The set of tubes B nearer the boiler and farther from the fire-box door is preferably composed of a larger number of tubes than the first set, owing to the fact that the heat 45 is greatest toward the rear of the fire-box.

In order to provide for access to the water-tubes for the purpose of removing scale or incrustation or otherwise cleaning the tubes and for repairing or renewing them, removable doors E E are fitted on the outer shell D at both sides of the fire-box, these doors being seated on and secured by screw studs or bolts to flange-pieces F, riveted around the doorways. These doors may be hinged with slotted 55 brackets to allow the door to be drawn clear of the studs or bolts and then swung around out of the way.

Having now described the invention, what I claim, and desire to secure by Letters Patent, is—

The combination with a boiler having tubes H, and a fire-box, the fire-box having double sides with water-spaces between them, of a plurality of sets of inclined water-tubes in the 65 fire-box and between opposite side spaces; the first set of tubes being near the door of the fire-box and inclining in one direction; the second set being nearer the rear of the fire-box; consisting of a larger number of tubes, 70 said tubes inclining oppositely to those of the first set.

In witness whereof I have hereunto set my hand in presence of two witnesses.

DUGALD DRUMMOND.
